UNITED STATES PATENT OFFICE

CARL E. CHRISTOPHEL, DECEASED, LATE OF PEARL RIVER, NEW YORK, BY THE FIRST NATIONAL BANK AND TRUST COMPANY OF PEARL RIVER, NEW YORK, EXECUTOR; SAID CHRISTOPHEL ASSIGNOR TO DEXTER FOLDER COMPANY, OF NEW YORK, N. Y., A CORPORATION OF NEW YORK

SHEET FEEDING DEVICE

Original application filed August 14, 1924, Serial No. 732,046. Divided and this application filed January 3, 1927. Serial No. 153,772, and in Great Britain August 10, 1925.

The present invention is an improvement in feeder and detector devices for controlling the feed of sheets to the front stops of printing or like machines, but adapted for use in any association where such a device is desired.

The principal object of the invention is to provide a simplified sheet detector mechanism at the slow-down device and press guides which operates if the sheet is out of alignment or if the sheet is missing to stop the feeding mechanism and trip the press, or to stop the press or both. Heretofore, a part of these detectors has been mounted on the press guides and a part on the front end of the feeder. Their structure and adjustments were complicated. In addition, the detector finger engaged the front edge of the sheet before it was positioned against the press guides and the action of the detector finger frequently displaced the sheet. Indeed it was sometimes necessary on small sheets to disconnect the detector. These disadvantages have been obviated and the detector simplified and made more readily adjustable by mounting the complete detector on the sheet support and by removing the detector finger from engagement with the sheet preferably by the action of the shaft that carries the slow-down mechanism. As soon as the upper slow-down element is elevated, the detector finger is removed from engagement with the sheet. A further advantage has been secured by associating the delivery detector, which operates if the sheet is being improperly delivered from the impression cylinder, with the sheet detector in such a manner that when the delivery detector is operated it will act through the sheet detector to stop the machine by the same mechanism that is employed by the sheet detector.

A further advantage is to provide a simplified, sensitive and yet positive control mechanism for tripping and stopping the press under the action of the sheet and delivery detector devices. To this end there has been provided a control disk adapted to be released upon the operation of the detectors, and a power device controlled by said

disk and having a part engaging the disk slightly off center with respect to the axis on which the disk is mounted. This power device is provided with connections for tripping the press and preferably also with means for opening or closing (as the case may be) the motor circuit. If the press is not electrically operated means may be associated with the power device for shifting a belt and applying a brake in addition to the means for tripping the press.

The invention will be better understood by reference to the accompanying drawings illustrating one embodiment of the inventive idea, and wherein—

Fig. 1 is a side view of a printing press of the flat-bed variety with which is associated a feeder equipped with detector and trip devices embodying the present invention;

Fig. 2 is a side view of the feeding mechanism, with certain parts removed for the sake of clearness, and showing the conveyor and the forward section of the sectional feed board in full and dotted line positions;

Fig. 3 is a detail, showing the drive from the intermediate press gear to the devices at the front of the feeder including the shafts carrying parts of the detector mechanism;

Fig. 4 is a perspective view showing the mechanism at the front end of the feed board and including the slow-down and sheet straightening and front registering devices, the side registering devices, the press guides, the sheet detector mechanism and the delivery detector at the cylinder;

Fig. 5 is a perspective view of the front end of the feed board, the same being shown in elevated position;

Fig. 6 is a longitudinal elevation, partly in section, showing the sheet detector mechanism and the delivery detector at the press cylinder; and Fig. 7 is a corresponding perspective view;

Fig. 8 is a perspective view with various parts omitted and other parts separated, showing the sheet detector mechanism and the operation of the device controlled thereby for tripping and stopping the press; and Fig. 9 is a detail of the same;

Fig. 10 is an elevation of the trip disk and associated parts; and

Fig. 11 is a view at right angles to that of Fig. 10.

5 Referring to the drawings, wherein like reference characters designate like parts throughout the several views, it is pointed out that the present application is a division of co-pending application Serial No. 732,046, filed August 14, 1924, and that the invention is shown, for purposes of illustration, in association with a printing press of the well-known flat-bed type. The invention is, however, adapted for other uses and purposes. 15 In the apparatus shown, the drive for the various instrumentalities at the forward end of the feed board is preferably obtained from an intermediate gear 50 of the press, which gear is driven from any suitable source of power 20 51 through a belt 52 and a pulley 53 mounted on a shaft 54 carrying a pinion 55 which meshes with and drives said intermediate gear 50. This intermediate gear meshes with and drives the cylinder gear 56 mounted on 25 a shaft 57 on which the impression cylinder 58 is carried.

The drive of the devices at a forward end of the feed board is effected through a gear 59 that meshes with the intermediate gear 50. 20 Gear 59 has compounded therewith a bevel gear 60 that meshes with a bevel gear 61 mounted on one end of a shaft 62 provided with two universal connections 63 and 64. The other end of shaft 62 is provided with a 25 gear 65 that drives the devices at the forward end of the feed board through a flexible shaft 66 and gears 67 and 68, the gear 67 being an idler gear mounted on the stub shaft 69. Adjacent the gear 65 is a bevel gear 70 that 30 meshes with a bevel gear 71 mounted on the lower end of a short vertical shaft 72 journaled in a gear casing 73 that is pinned to a shaft 74 journaled in suitable bearings on one of the side frames of the printing press. This 35 shaft 74 preferably carries a sheet feeding apparatus such, for example, as disclosed in co-pending application Serial No. 732,046, filed August 14, 1924. The short vertical shaft 72, through the medium of suitable 40 gearing, serves to drive a conveyor 75 passing over a feed board 76 and delivering the sheets from the pile elevating and sheet feeding mechanism to the front stops of the press. The conveyor 75 and feed board 76 may be 45 of any suitable construction, but the same are preferably of the type disclosed in the co-pending application above referred to.

The flexible shaft 66 carries on its forward end a bevel gear 77 that meshes with a bevel gear 78 on a stub shaft 79 that carries a pinion 80 meshing with a gear 81 carried by a stub shaft 82. This gear 81 is provided with a cam groove 83 on its outer face in which 50 engages a roller 84 carried by an arm 85 secured on the end of a shaft 86 journaled in

suitable bearings on the forward end of the feed board 76. This shaft 86 carries the upper members 87 (Fig. 4) of a side registering mechanism, such for example, as disclosed in co-pending application Serial No. 732,046 70 filed August 14, 1924. On the inside of gear 81 is formed a second groove 88 (Fig. 4) in which engages a roller 89 carried in the free end of an arm 90 mounted on a tube 91 also journaled in suitable bearings on the forward end of the feed board 76. The tube 91 is thus oscillated by the described connections therefor with the gear 81, and on this tube 91 is mounted the upper members 92 of slow-down, sheet straightening and registering mechanism such as disclosed for example in the co-pending application above referred to. Meshing with gear 81 is a pinion 93 mounted on one end of the shaft 94 which is journaled in suitable bearings on the forward end of 80 the feed board 76 at the under side thereof. This shaft 94 carries and drives the lower members 95 and 96 of the slow-down and side registering devices above referred to.

The sheet detector of the present invention 90 operates to trip the press or other instrumentality in the event that no sheet is delivered to the press guides 97. Each of these guides is carried by an arm 98 mounted on the front guide shaft 99 mounted in suitable bearings on the side frames of the press above the impression cylinder 58. This guide shaft is periodically raised and lowered during the normal operation of the machine and each press guide has a pair of curved spring members 100 which straddle and bear upon a tongue 101 projecting from the forward edge of the feed board adjacent the lower slow-down member or rollers 95 and 96. In the event that the sheet is improperly presented to the press guides, the sheet detector, by tripping the press, prevents the operation of the impression cylinder. 100

This detector mechanism preferably comprises an arm 102 which is carried by the tube 91 that carries the slow-down, straightening and registering mechanism and is secured thereon by means of a set screw 103 which bears on a key 104 carried in a keyway 105 of the tube 91 (Figs. 6 and 7). This arm 102 is provided with an extension 106 which is adjustable longitudinally of the arm 102 by means of a pin and slot connection 107. A rod 108 is carried in the tube 91 to rotate independently thereof, and to this rod there is secured in any desired manner, as by a screw threaded connection, an arm 109. The arm 109 is in two parts and may be lengthened or shortened by means of a sleeve 110 and an adjusting screw 111. In the free end of the arm 109 is pivoted at 112 a pendant 113. Also mounted on the pivot 112 is a second pendant 114 which is normally held in the position shown in full lines in Fig. 6. 110

The arm 102 being carried by the tube 91 115

that carries the slow-down and sheet straightening and registering mechanism, it will be appreciated that said arm is vertically oscillated with the slow-down and sheet straightening and registering mechanism. Just before the sheet reaches the press guides and after it has been operated upon by the slow-down and sheet straightening and registering mechanism, the front edge of the sheet engages the pendant 113 and swings it toward the left as seen in Fig. 4. This permits the arm 102 to freely rise as the tube 91 is oscillated. In the event that no sheet comes in contact with the pendant 113, the parts will remain in the position shown in Fig. 6, with the end of the extension 106 engaging the shoulder 115 on the pendant 113. Accordingly, as the arm 102 is elevated, the arm 109 will likewise be elevated thus rotating the rod 108. The rotation of the rod 108 effects the tripping of the press.

On the end of the rod 108 is mounted an arm 116 (Fig. 4) between the free end of which and the feed board is a compression spring 117 that tends to hold the arm 109 in the position shown in Fig. 6. Also mounted on the end of the rod 108 is a second arm 118 to which is pivoted a depending part 119. The lower end of this depending part is provided with a hook 120 over which engages one end of a link 121, the other end of the link being secured to one arm 122 of a bell crank lever pivoted at 123 (Fig. 8). The other arm 124 of the bell crank lever carries a roller 125 that engages in a notch or cutout portion 126 in a cam disk 127 pivoted on a stub shaft 128, carried in a casting 129 secured to one of the side frames of the press. This cam disk 127 is provided with a cam slot 130 in which engages a roller 131 mounted on the upper end of a power device. This power device includes a plunger 132 which projects into a cylinder 133 of the casting 129 and carries a piston 134 between which and the top of the cylinder there is confined a compression spring 135 which normally tends to force the parts associated therewith downwardly.

The lower end of the plunger 132 projects through the lower end of the cylinder 133 and is connected to the upper end of a link 136, the lower end of which is connected to a lever 137 pivoted at 138, which lever is provided with a cam face 139 that engages the edge 140 of a foot treadle 141 carried on the upper end of a treadle arm 142. This treadle arm passes through an opening 143 in a foot board 144 and is provided on each side with a fin 145, the fins being spaced from the lower side of the treadle a distance corresponding approximately to the thickness of the foot board 144. As will be hereinafter more fully described, when the treadle 141 is depressed the fins 145 will engage the under imperforate

part of the foot board and hold the parts in a depressed, locked position.

The lower end of the foot treadle arm 142 is pivoted to the free end of an arm 146 which is carried on a transverse shaft 147, 70 and a spring 148 connected at one end to the arm 146 and anchored at the other end to the frame of the press by means of a hook 149, tends normally to hold the parts in an elevated position. On the end of the transverse shaft 147, remote from the arm 146, is mounted a lever 150 provided with a cam slot 151 that engages a roller 152 carried on an arm 153, the operation of which trips the press in any usual or well known manner. Through the connections described the impression cylinder will be tripped. Power is preferably cut off either by opening or closing the electric circuit, as the case may be, when the plunger 132 is depressed. 75

Carried on the upper end of the plunger 132 is a transverse arm 154 in the free end of which is carried a rod 155 provided with a cam face 156 that is adapted to rock a bell crank lever pivoted at 157. One arm 158 of the bell crank lever carries the switch contacts or other means for opening or closing a circuit, and the other arm 159 of the bell crank lever carries a roller 160 that is engaged by the cam 156. A spring 161 tends to hold the parts in the position shown in Fig. 8. As the plunger 132 is lowered, the cam 156 will engage the roller 160 and rock the bell crank lever to open the contacts. 85

The member 155 is made adjustable in the arm 154 by means of a set screw 162. The reason for this is that it is sometimes necessary to operate on an open circuit arrangement. When this is the case the cam 156 will normally engage the roller 160 to hold the arm 158 away from the contacts. Under these conditions, when the plunger 132 is lowered the power will be cut off by engagement of the contacts, this being effected by the cam surface 156 passing out of engagement with the roller 160. 95

As the plunger 132 is lowered by spring 135, when roller 125 is released from the notch 126 of disk 127, it will be understood that the treadle lever will be depressed through the opening 143 in the foot board 144 until the fins 145 have passed through the board. The action of the cam 139 at that time will cause the foot treadle to be swung toward the left to the dotted line position (Fig. 9) so that the fins will then engage the under side of the foot board, and the parts thus locked in that position. When it is desired to return the parts to their set or normal position, this may be readily effected by bearing down on the pedal member 163 which will rock the lever 137 around the pivot 138, thus returning the plunger and 105 111 120 125 130

associated parts to their uppermost position and automatically repositioning the roller 125 in the notch 126, the roller snapping into this position under the influence of a spring 164 which encircles the pivot 123. After this has been effected, the press cylinder is released by moving the foot treadle slightly to the right so that the fins 145 will again assume the position shown in full lines in Fig. 7, under the influence of the spring 148.

It is pointed out that the roller 131 that engages and rides in the camway 130 is not positioned in exact alinement with the stub shaft 128, but is arranged slightly eccentric thereto as clearly shown in the dotted line position 131' in Fig. 10. The reason for this is to insure a facility of rotation of the cam disk 127 when the roller 125 is rocked out of engagement with the notch 126.

In view of the fact that the roller 131 is mounted so nearly concentric with the axis of the shaft 128, it requires very little effort to remove the roller 125 from the notch 126. In view of the necessity for a strong spring 135 and in view of the fact that it is desirable to release the spring by a very slight effort, it will be appreciated that the particular eccentric mounting of the roller 131 with respect to the axis of the stub shaft 128 is a matter of importance inasmuch as it secures a firm and positive control of a large force in a positive and yet sensitive manner. While the device, as illustrated, is shown in association with a control for an electric circuit, it will be understood that many presses are driven by belt power and that this same mechanism is adapted for the shifting of the belt from a tight to a loose pulley.

In order to facilitate the removal of the pendant 113 after the same has been engaged by the free edge of the sheet and to prevent said pendant from unduly pressing upon or interfering with the advance of the sheet, a cam 165 is preferably mounted thereon, which cam is engaged by the extension 106 as the arm 102 is elevated thus camming the pendant 113 upward and outward and away from the sheet.

The second pendant 114 which, as heretofore described, is pivoted on the axis 112, is provided with a horizontal arm 166 which projects forwardly and is normally engaged by a short arm 167 of a delivery detector 168 pivoted at 169 on a stay shaft 170. The delivery detector 168 may be adjusted angularly about the stay shaft 170 by means of an adjusting screw 171, and said detector may be raised or lowered with respect to the press stripper fingers 172 by means of a telescoping connection 173. The detector 168 may also be adjusted longitudinally of the stay shaft 170 and, in view thereof, the short arm 167 of the detector is provided with an extended surface 174 that engages the under surface of the arm 166. This short arm 167 is adjust-

able with respect to the arm 166 by means of the set screw 175.

In the normal operation of the parts, when sheets are being delivered from the impression cylinder 56, the delivery detector 168 and associated parts occupy the position shown in full lines in Fig. 6. If, however, a sheet should be improperly delivered from the impression cylinder, the detector 168 would be elevated to the dotted line position shown in Fig. 6 by the buckling or crumpling of the sheet, thus lowering the short arm 167 of the detector to the dotted line position, and thus permitting the arm 166 to lower to the dotted line position 166'. This would accordingly permit the second pendant 114 to swing down into a position where the shoulder 176 thereon would be engaged by the extension 106 on the next elevation of the arm 102. When this is effected the rod 108 would be rotated as heretofore described in connection with pendant 113 and the operation of the control mechanism to trip the impression cylinder and stop the press would be repeated.

In order to insure the proper engagement of the sheets with the pendant 113, there is preferably provided a plate 177 (Figs. 6 and 7) mounted on a bracket 178 carried by a T-slot bar 179 secured on the forward end of the feed board. The plate 177 has a cutout portion 180 in which the free end of the pendant 113 normally engages, and in which the free end of the second pendant 114 engages when it is lowered by the operation of the delivery detector as above described.

While one expression of the inventive idea has been heretofore described and illustrated in detail, it is to be expressly understood that the invention is not limited thereto, and that the inventive idea may be embodied in various mechanical expressions within the limits of the appended claims.

What is claimed is:

1. In combination, a sheet support, a sheet detector mounted thereon and having two relatively movable members one of which rocks, a pendant carried by the other of said members and adapted to be engaged by the rocking member, means for operating the rocking member and moving the pendant carrying member by the rocking member when the latter engages said pendant, stop mechanism, and connections between the pendant carrying member and said stop mechanism for operating the latter when said pendant carrying member is moved as aforesaid.

2. In combination, a sheet support, a sheet detector mounted thereon and having two relatively movable members one of which rocks, a pendant carried by the other of said members and adapted to be engaged by the rocking member upon non-delivery of a sheet past the pendant, means for operating the

rocking member and moving the pendant carrying member by the rocking member when the latter engages said pendant, stop mechanism, and connections between the pendant carrying member and said stop mechanism for operating the latter when the pendant carrying member is moved as aforesaid, said pendant being provided with a cam surface which is engaged by the rocking member to remove the pendant from the path of sheets delivered past said pendant.

3. In combination, a sheet support, a sheet detector mounted thereon and having two relatively movable members one of which rocks, a pair of pendants carried by the other of said members and adapted to be engaged by the rocking member, means for operating the rocking member and moving the pendant carrying member thereby when either of said pendants is engaged with said rocking member, stop mechanism, connections between the pendant carrying member and said stop mechanism for operating the latter when the pendant carrying member is moved as aforesaid, a delivery detector, and connections between said delivery detector and one of said pendants.

4. In combination, a sheet support, a sheet detector mounted thereon and having upper and lower relatively movable members, a sleeve on which the lower member is mounted, a rod on which the upper member is mounted and projecting through said sleeve, a pendant carried by the upper member and adapted to be engaged by the lower member, means for moving said rod through said pendant when the latter is engaged by said lower member, stop mechanism, and connections between said rod and said stop mechanism for operating the latter when the rod is moved as aforesaid.

5. In combination, a sheet support, a sheet detector mounted thereon and having two relatively movable members, a rocking tubular element on which one of said members is mounted, a rod on which the other of said members is mounted and projecting through the rocking tubular element, a pendant carried by the member mounted on said rod and adapted to be engaged by the other member, means for rocking the tubular element and adapted to move said rod through said pendant when the latter is engaged by said last named member, stop mechanism, and connections between said rod and the stop mechanism for operating the latter when the rod is moved as aforesaid.

6. In combination, a sheet support, a sheet detector mounted thereon and having two relatively movable members, a pendant carried by one of said members and adapted to be engaged by the other member, means for continuously rocking the last named member and adapted to move the pendant carrying member when said pendant is engaged

by the continuously rocking member, stop mechanism, and connections between the pendant carrying member and said stop mechanism for operating the latter when the pendant carrying member is moved as aforesaid.

7. In combination, a sheet support, a sheet detector mounted thereon and having two relatively movable members, a pair of pendants carried by one of said members and adapted to be engaged by the other member, means for moving one of said members by the other through either of said pendants, stop mechanism, connections between one of said members and said stop mechanism, a delivery detector, and an elongated engaging surface carried by said delivery detector adapted to engage one of said pendants.

8. In combination, a mechanism to be controlled, a detector, a pivoted disk, connections between said detector and disk normally holding the latter stationary and released from said disk when the detector is operated, a power device controlled by said disk and having a connection thereto slightly off center, and connections between said power device and said mechanism for tripping the same when the connections for the detector with the disk are released therefrom.

9. In combination, a mechanism to be controlled, a detector, a pivoted disk, connections between said detector and disk normally holding the latter stationary and released from said disk when the detector is operated, a power device controlled by said disk and having a connection thereto slightly off center, connections between said power device and said mechanism for tripping the same when the connections for the detector with the disk are released therefrom, an electrical circuit, and connections between said power device and said circuit for controlling the same.

10. In combination, a mechanism to be controlled, a detector, a pivoted disk, connections between said detector and disk normally holding the latter stationary and released from said disk when the detector is operated, a power device controlled by said disk and having a connection thereto slightly off center, connections between said power device and said mechanism for tripping the same when the connections for the detector with the disk are released therefrom, and means controlled by said power device for stopping the mechanism.

11. In combination, mechanism to be controlled, a detector, a control disk having a peripheral notch and a slot, connections between said detector and said control disk and including a lever normally engaged in said notch, a power device controlled by said disk and including a plunger engaged in said slot, and connections between said plunger and said mechanism for tripping the same.

12. In combination, mechanism to be controlled, a detector, a control disk having a peripheral notch and a slot, connections between said detector and said control disk and including a pivoted trip lever normally engaged in said notch, a power device controlled by said disk and including a movable member engaged in said slot, and connections between said member and said mechanism for stopping the same.

13. In combination, mechanism to be controlled, a detector, a pivoted disk having a peripheral notch, connections between said detector and the disk including a member normally engaged in said notch, a power device controlled by said disk and comprising a spring pressed plunger engaged in a slot of the disk, and connections between said plunger and said mechanism for tripping and stopping the same.

14. In combination, mechanism to be controlled, a sheet detector, means for actuating the detector upon failure of delivery of a sheet past the same, a notched control element, connections between said detector and element including a member normally engaged in the notch thereof to hold the element stationary and adapted to be disengaged from said notch when the detector is operated and thereby provide for movement of the element, a power device controlled by said element and comprising a spring pressed plunger engaged in a slot thereof, and connections between said plunger and said mechanism.

15. In combination, mechanism to be controlled, a sheet detector, means for actuating the detector upon failure of delivery of a sheet past the same, a pivotally mounted control element, connections for the detector with the control element normally engaged therewith to hold the same stationary and released therefrom when the detector is operated, a power device controlled by said element including a cylinder and a spring pressed plunger extending in said cylinder and connected with the control element in a slot thereof, connections between said plunger and said mechanism, an electric circuit, and means movable with said plunger exteriorly of the cylinder for controlling said circuit.

16. In combination, a mechanism to be controlled, a detector, a rotatably mounted control element having a groove extending radially from its axis of rotation, connections between said detector and element normally preventing its rotation and releasable therefrom when the detector is operated, a power device controlled by said element and provided with a plunger connected therewith in the groove thereof, and connections between said plunger and said mechanism including a foot treadle adapted to be locked in tripped position when said plunger is operated, and

means for locking said foot treadle in said position.

17. In combination, a mechanism to be controlled, a detector, a notched rotatably mounted control element having a groove extending radially from its axis of rotation, connections between said detector and the notch of said element and released therefrom when the detector is operated, a power device controlled by said element and provided with a plunger connected therewith in the groove thereof, and connections between said plunger and said mechanism including a foot treadle adapted to be locked in tripped position when said plunger is operated.

18. In combination, a mechanism to be controlled, a detector, a rotatably mounted disk having a notch and a groove, connections between said detector and the notch of said element and released therefrom when the detector is operated, a power device controlled by said element and provided with a plunger, means slidably connecting the plunger with said element in the groove thereof, and connections between said plunger and said mechanism including a resetting lever and a foot treadle operated by said lever.

19. In combination, a mechanism to be controlled, a detector, a disk having a notch in its periphery and a radially extending groove, connections between said detector and the disk including a member normally engaged in said notch, a power device controlled by the disk including a cylinder and a plunger extending therethrough and connected with the said disk in the groove thereof, connections between the plunger and said mechanism for tripping the same, and connections between said plunger and said mechanism for stopping the same.

20. In combination, a mechanism to be controlled, a detector, a control element, connections between said detector and element, a pivoted disk provided with a slot, a power device controlled by said element including a plunger, a roller carried by said plunger and engaging said slot slightly off center of the axis of rotation of said disk, and connections between said plunger and mechanism.

In testimony whereof said executor, by its president, has signed this specification.
